UNITED STATES PATENT OFFICE.

HENRIETTA L. KELSEY, OF PHILADELPHIA, PENNSYLVANIA.

KNITTING-NEEDLE.

1,327,918.

Specification of Letters Patent. Patented Jan. 13, 1920.

Application filed March 19, 1918. Serial No. 223,284.

To all whom it may concern:

Be it known that I, HENRIETTA L. KELSEY, a citizen of the United States, residing at Philadelphia, in the county of Philadelphia and State of Pennsylvania, have invented 5 certain new and useful Improvements in Knitting-Needles, whereof the following is a specification, reference being had to the accompanying drawings.

10 The invention relates to improvements in needles, such as are ordinarily employed in hand knitting or crocheting.

Knitting of this sort is very much in vogue at the present time, and is extensively practised under various conditions in public 15 places, such as theaters, etc., which, during certain periods, are sparsely illuminated.

In order to facilitate the use of these implements in darkness or semi-darkness, my 20 invention has been directed to providing needles of this type with luminous points, which are plainly visible under such conditions.

This I accomplish by applying a luminous 25 material, either internally or externally at the region of the point of the needle, with provision for protecting the same against wear occasioned by extensive usage.

In the accompanying drawings, Figure I, 30 is a perspective view of a knitting needle conveniently illustrating my invention.

Fig. II, is a longitudinal sectional view on an enlarged scale through the pointed end of the same.

35 Fig. III, is a view illustrating a modified form of my invention.

The needle 1, is made of celluloid or similar transparent material in rod form, having a circular cross section. The rod is cut to 40 the proper length and the retaining knob 2, formed in any well known manner. In order to accommodate the luminous material, I prefer to bore that end of the needle which ultimately becomes the point, to the 45 depth proportionately indicated at 3, in Fig. II, and to apply the luminous material 5, in paint form to the interior walls of the cavity. After this has set, the end of the rod may be sufficiently heated to permit the 50 point to be drawn or rolled to the desired shape illustrated. By this construction the luminous material is effectively protected by the overlying transparent material of the needle with the result that the needle can

be used indefinitely without impairing its 55 efficiency. If desirable, the needle may be formed wholly of tubular material, and the luminous paint applied internally throughout its length, but for all practical purposes, and in view of the high cost of the luminous 60 paint, it is deemed sufficient to apply the same only at the region of the point. Such luminous points are not only visible *per se*, but also render visible the yarn or thread 65 being knitted, both in silhouette and by reflected light.

The shape and position of the cavity or cavities containing the luminous material may vary as is found most convenient.

In the modification of Fig. III, after the 70 needle has been completely formed as an integral solid structure, the point is dipped to the desired extent as indicated at 10, into the luminous paint. A coating of lacquer or other transparent material is subsequently 75 applied over the painted surface, to protect the same against wear in the course of usage.

In both of the illustrated forms, the principle and function of the luminous point are the same, the difference residing only in the 80 method of application of the luminous material, and the manner of affording a protection therefor. It is to be understood that these ends may be accomplished in numerous other ways, and I, therefore, do not desire 85 to be limited to the precise details of arrangement and construction herein shown.

In double pointed needles it is desirable 90 to apply the luminous material to the region of both ends.

Having thus described my invention, I claim:

1. A needle for the uses set forth, having in the region of its pointed end luminous material protected against wear by overlying transparent material.

2. A transparent knitting needle having a hollow pointed end containing a luminous material, substantially as shown, and for the purpose set forth.

In testimony whereof I have hereunto signed my name at Philadelphia, Pennsylvania, this eighteenth day of March, 1918.

HENRIETTA L. KELSEY.
